FIG. 1

FIG. 2

FIG. 3

FIG. 4

FIG. 6

FIG. 5

FIG. 7

FIG. 1 is a perspective view of a valve receiving tubing clamp embodying my new design;

FIG. 2 is a side elevational view thereof;

FIG. 3 is an elevational view taken from the side opposite that shown in FIG. 2;

FIG. 4 is an elevational view taken from the right side of FIG. 3;

FIG. 5 is an elevational view taken from the left side of FIG. 3;

FIG. 6 is a top plan view of FIG. 3; and

FIG. 7 is a bottom plan view of FIG. 3.

The broken line representation of a valve and a line in FIGS. 1 and 2 is for purposes of illustration only.

I claim:

The ornamental design for a valve receiving tubing clamp, substantially as shown and described.
